MOUTHPIECE

Filed April 4, 1927

UNITED STATES PATENT OFFICE.

AUGUST PAULSON, OF REEDLEY, CALIFORNIA.

MOUTHPIECE.

Application filed April 4, 1927. Serial No. 180,831.

The device forming the subject matter of this application is a mouth piece for wind instruments of the flute type, and one object of this invention is to provide a mouth piece which will absorb the moisture in the breath of the performer, it being a matter of common knowledge that players on instruments of the sort mentioned often have occasion to pull off the head joint and blow the moisture out of it, to the end that the tone of the instrument may not be impaired.

Another object of the invention is to provide novel means for mounting the mouth piece so that it can be shifted at the will of an operator, with respect to the blow-hole, thereby to change the direction of the current of air, as is necessary, for instance, when the music shifts from the first octave to the second or third octave.

Another object of the invention is to provide a flexible member for disposition at the blow-hole of the instrument, to reproduce, closely, the results obtained by the flexible human lip, the said member being under the control of the tilttable mouth piece, and constituting, also, a spring means whereby the mouth piece is returned to an initial position.

The invention aims, moreover, not only to carry out the aforesaid results broadly, but to provide, specifically, a novel mechanism whereby the aforesaid improvements may be put into practice.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in plan, a device constructed in accordance with the invention, mounted on an instrument;

Figure 2 is an enlarged elevation, showing a device constructed in accordance with the invention, mounted on a portion of a wood-wind instrument;

Figure 3 is a section on the line 3—3 of Figure 2;

Figure 4 is an elevation showing the support whereunto the mouth piece is pivotally connected;

Figure 5 is a plan of the mouth piece; 60

Figure 6 is a side elevation of the mouth piece;

Figure 7 is a cross section on the line 7—7 of Figure 5;

Figure 8 is an elevation showing the inner 65 end of the mouth piece and attendant parts;

Figure 9 is a cross section on the line 9—9 of Figure 3.

In carrying out the invention, there is provided a mouth piece 1 including a flexible absorbent body 2 made out of any preferred material, such as plaster of Paris, or a plaster of Paris compound. The body 2 has a longitudinal passage 3 through which air passes when the instrument 12 is blown. 70 Preferably, but not of necessity, the body 2 is enclosed within a metal casing 4 provided near to its inner end with a depending U-shaped yoke 5. Between the yoke 5 and the inner end of the casing 4, the casing is supplied with laterally outstanding ears 6 provided at their inner ends with hinge knuckles. Across the bottom of the casing 4, and, if desired, secured to the bottom of the casing, 75 is extended a reinforcing and abutment strip 8 provided with a depending flange 80. The strip 8 is called a reinforcing strip, because its ends are formed into hooks 9 that extend about the ears 6 and strengthens them. 80

The device includes a support 10 which 90 may be a metal plate, provided with inner arms 11 and with outer arms 14. The support 10 rests against the instrument 12, and is held thereon by metal bands 16 which pass around the instrument 12 and between the 95 arms 11 and 14 of the support 10, the ends of each band 16 being connected by draw bolts 17. The arms 11 and 14 are provided at their ends with knuckles 15. The mouth piece 1 is so placed that its knuckles 7 are 100 disposed between the knuckles of the inner arms 11 of the support 10, as shown in Figure 2. Headed pivot elements 18, are mounted in the knuckles 15 of the arms 14 and 11 on the support, and the inner ends of the 105 pivot elements 18 are received in the knuckles 7 of the mouth piece 1. The mouth piece, thus, is mounted for swinging movement in a direction at right angles to the axis of the fife or other like instrument shown at 12. 110

The support 10 is provided intermediate its ends with a reduced part 19 which is

folded on itself as at 20, to form an outer wall 21 having a projecting ledge 22. The wall 21 has rearwardly extended flanges 23 carrying a pivot member 24 on which is mounted a shackle 25 which is detachably engaged with the yoke 5. A spring 26 is engaged around the pivot member 24, the spring 26 bearing against the wall 21 of the support 10 and against the lower portion of the hook-shaped shackle 25. The function of the spring 26 to hold the shackle 25 in the position delineated in Figure 3, and in engagement with the yoke 5. A piece of rubber 27, or other flexible material, is folded upon itself, as is shown in Figure 3. The lower edge of the flexible resilient member 27 rests on the ledge 22 of the support 10, and the upper part of the member 27 is located in front of the flange 80 and in close relation to the lower inner edge of the mouth piece 1, as shown in Figure 3. The member 27 extends partway across the blow-hole 28 of the fife or other instrument 12.

The mouth piece 1 may be swung in a direction at right angles to the axis of the instrument 1, so as to vary the line in which the air proceeding through the passage 3 is directed into the blow-hole 28 and in this way, a result is obtained, which simulates, very closely, the result produced when the fife is blown directly from the human lips, without the interposition of a mouth piece. The tone is improved, moreover, because the steam of air, spreading as it flows out of the inner end of the passage 3, flows over the flexible member 27. This member 27, being flexible, produces very much the said effect as that brought about when the lower lip of a player is placed against the instrument at the blow-hole 28. As the mouth piece 1 is swung at right angles to the axis of the instrument 12, the flange 80 presses the upper part of the member 27 inwardly and outwardly and the tone is altered accordingly, just as it may be altered by a flexure of the human lip. The amount that the mouth piece 1 may be swung at right angles to the axis of the instrument 12 is limited by the shackle 25 which is engaged with the yoke 5. The spring 26 holds

the shackle 25 engaged with the yoke 5, but the operator can swing the shackle 25 clear of the yoke 5. This may be desirable, when the operator desires more freedom of swinging movement in the mouth piece 1 than the shackle 25 will allow. The shackle 25, may be disengaged from the yoke 5, moreover, when it is desired to renew the resilient member 27 or to shift the position thereof.

What is claimed is:—

1. A mouth piece for wind musical instruments, the mouth piece being made of flexible absorbent material.

2. A mouth piece for musical instruments of the flute type, means for mounting the mouth piece for adjusting movement relative to the blow-hole of the instrument by means of the lips of the player and whilst the mouth piece is in use, and spring means for yieldably holding the mouth piece during its aforesaid movement.

3. A wind musical instrument of the flute type, having a blow-hole, a bendable resilient member partly covering the blow-hole, and a mouth piece discharging into the blow-hole across the bendable, resilient member.

4. A wind musical instrument of the flute type, having a blow-hole, a bendable, resilient member partly covering the blow-hole, a mouth piece, means for mounting the mouth piece for swinging movement, and means embodied in the mouth piece for changing the shape of the bendable, resilient member, as the mouth piece is swung.

5. A mouth piece for musical instruments of the flute type, having a blow-hole, means for mounting the mouth piece for swinging movement relative to the blow-hole, by means of the lips of the player, and whilst the mouth piece is in use, and spring means for governing the swinging movement of the mouth piece, said spring means being a flexible member extended partway across the blow-hole, the mouth piece having means for changing the shape of said member, as the mouth piece is swung.

In testimony that I claim the foregoing as my own, I have hereto affixed my signature.

AUGUST PAULSON.
